DANIEL G. ADAMS, OF NEW YORK, N. Y., ASSIGNOR TO ADAMS GREASE GUN CORPORATION, OF NEW YORK, N. Y., A CORPORATION OF NEW YORK

LUBRICATING MEANS

Application filed April 11, 1929. Serial No. 354,367.

This invention relates to grease guns, and particularly to an improved one-hand gun, the object being to provide a construction which is highly efficient and which may be applied and actuated by one hand.

Another object of the invention is to provide a grease gun or lubricating means for automobiles or other machinery, wherein means are provided not only for forcing 10 grease to the desired part, but for engaging a coupling for holding the grease-carrying portion in position while the actuating means functions.

A further object, more specifically, is to 15 provide a lubricating means which includes a gun with a hand-propelled piston or plunger and means for automatically feeding grease to a position in front of the plunger upon each withdrawal of the plunger.

In the accompanying drawing—

Figure 1 is a side view of a grease gun disclosing an embodiment of the invention;

Figure 2 is a longitudinal vertical sectional view through Figure 1, the same being 20 shown on an enlarged scale;

Figure 3 is a view similar to Figure 2 but showing the respective ends broken away and the piston in an operated position;

Figure 4 is a transverse sectional view 25 through Figure 3 on the line 4—4;

Figure 5 is a detail perspective view of a holding plate and associated parts embodying certain features of the invention;

Figure 6 is a perspective view of the clutch 30 plate shown in Figure 2;

Figure 7 is a view similar to the left-hand part of Figure 2 but disclosing a modified construction.

Referring to the accompanying drawing by 35 numerals, 1 indicates a gun, 2 a coupling, and 3 a handle connected to the rod 4. These members all make up the lubricating means and may be used with different forms of coupling members, as for instance, the coupling member 5 or coupling member 6, or those

disclosed in my co-pending application, Serial No. 329,361. Preferably the coupling 2 is provided with slots 7 so as to receive the pins of either of the coupling members 5 or 6. When the device is to be used it is placed 50 on the coupling member, as shown in Figs. 2 and 7, and then the handle 3 is moved back and forth, whereby grease will be forced from gun 1 into the coupling member and thence to the part to be lubricated. The coupling 55 members 5 and 6 may be of a type shown in my co-pending application or any other desired type, provided they are supplied with pins or other means which may coact with the coupler 2. The coupler 2 is preferably 60 screwed onto the neck 8 of the gun 1, as shown in Figure 2, whereby it may be applied or removed at any time. Neck 8 interiorly is provided with a bore 9 which acts as a high pressure chamber or cylinder and 65 is adapted to receive grease at one time and the piston at another time, as shown in Figure 3. The ball valve 11 normally closes the outlet to the chamber 9, said ball being normally maintained seated by the spring 12 70 resting on the shoulder 13. Adjacent the shoulder 13 is a passageway 14 having a beveled portion 15 and a juncture 16 between these two portions forming a dirt-cutting 75 edge against which the beveled or tapered part 17 of the coupling member 5 presses. This dirt-cutting edge is important, in that it provides a good seal, notwithstanding the fact that the grease is forced into the coupling member 5 under high pressure, as for 80 instance, several thousand pounds per square inch. In the modified form as shown in Figure 5, the male coupler member 6 is not provided with a projection carrying a beveled portion 17, as shown in Figure 2, and consequently the female coupler member 2' is supplied with a nipple 18 screwed or otherwise fitted into the coupler member 2' and positioned so that the edge 19 of the coupler member 6 will strike the beveled portion of the 85 90

nipple and thereby produce a dirt-cutting edge and seal. Aside from these features the construction is identical with that shown in Figure 2.

5 In order that the grease may be forced intermittently past valve 11 into what may be termed the compression chamber 20 and thence through the coupler member 5, plunger 10 is intermittently forced into the chamber 9 where it has a rather snug, sliding fit, as shown in Figure 3. As the plunger enters the chamber 9 the grease forces valve 11 off its seat and then the added inflow of grease results in some of the grease flowing into and 10 through the coupler member 5 to the article to be lubricated. As soon as the piston has completed its full stroke and starts on its return stroke spring 12 will cause valve 11 to immediately close so that the pressure is 15 maintained in chamber 20 ready for the next stroke of the piston. As the piston leaves the chamber 9 a certain amount of vacuum or rarefaction is formed, whereby the grease is sucked into the chamber ready for a second 20 action of the plunger. This suction of the grease in the chamber is augmented by the action of spring 21 which is under compression, as shown in Fig. 3, and which, therefore, causes the washers 22 to force the grease 25 towards chamber 9. By reason of the action of spring 21 the grease is always under some slight pressure, and this pressure added to the vacuum or rarefaction caused by the removal of piston 10 will result in a quick 30 refilling of chamber 9. In addition, spring 21 acts to return the piston rod 4 and handle 3 to an outer position ready to be forced in again by the hand of the operator. When the lubricating means is first applied to the 35 coupler member 5 the parts are in the position shown in Figure 2. The operator presses handle 3 inwardly until the stop 23 strikes the end of member 24. The pressure by the hand is then relieved and spring 21 40 acts to force the handle 3 back to an outer position, so that the hand of the operator may again cause piston 10 to function. This back and forth motion is carried out until the article being lubricated has received the 45 desired amount of grease. The end 24 is provided with an air opening 25 so that the washers 22 and associated parts may properly act without producing any rarefaction or back pressure. In addition, a relief opening 26 is formed in the sleeve 27, whereby 50 air may pass through the enlarged bore 26' along the rod 4 to equalize the air pressure on both sides. This is very desirable when the device is being loaded or when the washers 22 and associated parts are being removed. From Figures 2 and 3 it will be seen that two 55 washers 22 have been provided, but if desired, one washer could be used or more than two. These washers are preferably of leather, although they could be made from other 60

material without departing from the spirit of the invention. Preferably a metallic washer 28 is arranged on one side of washer 22 and a second metallic washer 29 on the opposite side, washer 29 having a hub 30 which assists in holding the washer in place and causing a smoother back and forth movement. The sleeve 27 is provided with an abutment or turned-up end 31, whereby the washers can not be forced off the sleeve but spring 21 acts to hold the same adjacent abutment 31 whenever possible. Also, the parts are formed so that as the grease is forced from the gun by a back and forth movement of piston 10 and associated parts, certain mechanism will be operated for gradually feeding the washers 22 and associated parts toward the chamber 9. This mechanism consists of a clutch 32 having an aperture 35 slightly larger than rod 4, said rod 70 extending through said aperture, whereby when the clutch 32 is at an angle it will pinch the rod so that the washer and associated parts cannot move toward handle 3, except to the extent permitted by spring 21, as 75 shown in Figure 3. This clutch permits sleeve 27 to slide toward chamber 9 but normally prevents the same from sliding toward handle 3. The sleeve 27 at the end 80 nearest chamber 9 is burred or turned up for forming the flange 31, while at the opposite end it is slightly reduced, so that the plate 34 may fit thereover. This end of the sleeve is also riveted or burred for clamping plate 34 in position. This plate, as shown 85 in Figure 5, is provided with a bore 35 which fits over the reduced part of sleeve 27 and with a turned-up post 36 merging into the extension 37 which limits the upward swinging movement of the clutch 32. Plate 34 is 90 also provided with a turned-up portion 38 and on each side of this turned-up portion 38 are posts 38' and 38''. Each of these posts is provided with a turned-over end so that the extension 39 of clutch 32 is held in 95 proper operative position, while the extension 39' projects beyond post 36, whereby it may be engaged by the hand and raised to a position against the portion 37 when it is desired to pull the follower back to a point 100 near pin 42. A spring 41 is bent so as to fit over the end of extension 39 inside of the projection 38 and on top of the projection 39, as shown in Figure 2, whereby the clutch 32 is held normally in the position 105 shown in Figure 2. When the rod 4 is forced inwardly from the position shown in Figure 2 to that shown in Figure 3, spring 21 will be brought under tension and cause washers 110 22 to press against the grease while the piston 10 forces some of the grease past valve 11. On the return movement of rod 4 the suction or rarefaction in chamber 9 will draw some of the grease into the chamber 115 and this action will have a tendency to pull 120

the follower a short distance toward the chamber 9. Each time the device operates this action is repeated, and consequently, the follower is always in engagement with the grease. On the return movement the pin 42 limits the movement of the rod 4, while on the power stroke the pin 42' limits the movement. Pin 23 will act to limit the inward movement of the rod in case pin 42' should become broken or fail to function for any cause.

In operation when the parts are in the position shown in Figure 2, the gun is ready for use and is in engagement with the coupling member 5. By forcing the handle 3 and rod 4 inwardly to the position shown in Figure 3 a certain quantity of grease will be forced past valve 11. As soon as this has been done pressure on handle 3 is released sufficiently to permit the spring 21 to act, said spring having been brought under tension by the inward movement of sleeve 27. As the rod 4 moves outwardly under the action of spring 21 grease will flow into chamber 9 under the action of the pressure of spring 21 and under the action of the rarefaction produced in chamber 9. As soon as handle 3 has moved outwardly until stop 42 engages end 24 it is ready for a second operation. In this way the gun may be used with one hand and therefore may be used in many places where it is difficult to use two hands with some other form of gun. Also, by providing a comparatively small piston 10 and small chamber 9 a slight pressure exerted by the workman is sufficient to force grease into the parts to be lubricated under very high pressure.

When the gun is first loaded usually one or more air pockets are formed. These air pockets are quickly eliminated by reason of the vent through the bore 26' and the aperture 26. This air is forced out by the more or less constant pressure of the washers 22 against the grease under the action of spring 21. When the parts are in their full, inner position, as shown in Figure 3, the outlet 26 will be covered, but when the tension on spring 21 has been substantially relieved, opening 26 will be uncovered, as shown in Figure 2, and consequently air may freely pass therefrom. As the rod 4 reciprocates during the functioning of the pump the follower moves forward slowly intermittently, said movement being caused by the displacement of the grease which results from the suction or rarefaction formed in the chamber 9. By forming the parts in this manner a very high pressure may be given to the grease which is ejected and the air pockets may be quickly and automatically removed while the follower continually functions to remain in contact with the grease and provide a pressure thereon from time to time with the action of spring 21.

What I claim is:—

1. A lubricating means, including a one-hand grease gun and a pair of couplers co-acting therewith, one coupler being adapted to be permanently connected with the means to be lubricated and the other removably connected with the gun, the first-mentioned coupler having pins and the second-mentioned coupler having slots for receiving the pins, whereby the gun is held in proper alignment, said couplers having interengaging portions including a dirt-cutting sealing edge, whereby grease under high pressure can only pass into the coupler connected with the means to be lubricated.

2. A lubricating means, including a grease gun structure formed with a casing, a discharge nozzle connected with the casing, said nozzle being formed with an ejecting chamber, a piston positioned to move into and out of the chamber, a rod extending from the piston through the end of the casing opposite the nozzle, a handle carried by said rod, whereby the rod may be forced inwardly by one hand so as to cause the piston to function, and a follower carried by the rod, said follower having a washer structure, a clutch carried by said follower for clutching said rod and a spring acting on the washer structure and on the clutch for holding the washer structure under pressure, whereby the grease in the casing is fed automatically toward said chamber and said spring acts to return said rod and handle to a retracted position after each operation.

3. A lubricating means, including a coupler and a gun structure associated with the coupler, said gun structure including means forming an ejecting cylinder, a piston co-acting with said cylinder, a rod extending from said piston, a casing connected at one end with the means forming said chamber, and a follower carried by said rod positioned within said casing, said follower being formed with a sleeve slidably mounted on said rod, a washer slidably mounted on said sleeve and engaging said casing at its periphery, a clutch carried by said sleeve adapted to clutch said rod, and a spring acting on one end of the sleeve and on the washer for resiliently holding the washer in such a position as to maintain the grease in the casing under pressure and also to return said rod to a retracted position when released.

4. A lubricating means, including a grease gun formed with a casing, a rod extending into the casing, a piston carried by the rod positioned to eject grease from the casing when the rod is moved in one direction, a sleeve slidably mounted on the rod, said sleeve being provided with a turned-up end and with a pair of arms, a swinging clutch carried by one of said arms, said clutch extending to a position opposite the other arm, a spring acting to normally hold the clutch in

one position so as to pinch said rod, and means coacting with said clutch for maintaining the grease in the casing under pressure.

5. A lubricating means, including a grease gun formed with a casing an operating rod and a follower in said casing slidably mounted on said rod, said follower being formed with a sleeve having an aperture therein, a washer slidably mounted on the sleeve and normally positioned between the aperture and the end of the sleeve, a spring acting on the sleeve and on the washer for resiliently holding the same adjacent the end of the sleeve, and a clutch carried by the sleeve at the end opposite the washer, said clutch functioning to grip said rod when the follower attempts to move in one direction and to unclutch when the follower attempts to move in the opposite direction.

6. A lubricating means, including a gun having a casing adapted to receive a supply of grease an operating rod and a follower in said casing slidably mounted on said rod, said follower including a spring-pressed washer and a sleeve carrying said washer, said sleeve carrying a pair of arms at one end, one of said arms being formed with a pair of posts, holding means extending from the respective posts, a clutch member formed with an extension projecting between said posts and resting on the arm, and a spring carried by said arm extending beneath said holding means and acting on the clutch to hold the same normally in a clutching position.

7. A lubricating means, including a gun having a casing adapted to receive a supply of grease, a discharge nozzle for said casing, a piston for ejecting grease through said nozzle, a rod supporting said piston, said rod extending through the casing at the opposite end to said nozzle, and a follower slidably mounted on the rod, said follower including a clutch functioning to permit the follower to move in one direction of the rod and prevent the follower from moving in the opposite direction, said follower being also formed with a sleeve surrounding said rod, and a spring-pressed washer slidably mounted on the sleeve, said sleeve being formed with openings presenting a relief passageway extending normally from the pressure side of the washer to the opposite side for exhausting air trapped between the washer and the grease in said casing.

8. A lubricating means including a gun formed with a casing merging into a nozzle having an ejecting chamber, a piston positioned to move into and out of said ejecting chamber, a rod extending from said piston through the end of the gun, a handle carried by said rod exteriorly of the casing of the gun, and a follower mounted on said rod, said follower being formed to slidably fit the interior of said casing so that when said rod is moved

in one direction part of the grease therein will be ejected, a spring acting on said follower and on said rod for causing the rod to be retracted after each operation as well as to cause the follower to maintain the grease in the casing under pressure as said rod is retracted and the piston moved out of said ejecting chamber, whereby a new supply of grease from the casing will be forced into the compression chamber, and a clutch for clutching the follower to the rod, said clutch permitting said rod to be retracted at all times without rotation.

9. A lubricating means, including a gun formed with a casing, a discharge nozzle, a piston for forcing grease through the discharge nozzle, a rod extending from the piston to a point exteriorly of the casing, wherein by the piston may be operated, a spring-pressed follower carried by said rod, a connection between said follower and rod for connecting the follower to the rod at any point along the rod on inward movement of the rod, said rod being movable outwardly relative to said follower at all times without rotation of the rod and a coupler connected with said nozzle, said coupler formed with means for interlocking with part of the article to be lubricated.

10. A lubricating means, including a gun formed with a casing merging into a nozzle having a compression cylinder, said casing being adapted to receive a supply of grease, a rod extending into said casing, said rod being formed with a piston adapted to move into said compression chamber for forcing grease therefrom, and a spring and atmosphere pressed follower slidably mounted on said rod, a clutch for clutching said follower to the rod and preventing accidental return movement of the follower, said spring surrounding said rod and acting on said rod and said follower for the double purpose of assisting in causing said follower to continually press the grease toward said compression cylinder and cause a retraction of said rod after each operation.

11. A lubricating means, including a gun formed with a casing and a piston for ejecting grease from the casing, and a follower arranged in the casing for maintaining the grease under pressure, said follower including a sleeve, a sliding washer carried by the sleeve, a spring acting at one end on the sleeve and at the other end on the washer for resiliently holding the washer in a given position, a rod for actuating said follower, said rod extending through said sleeve and washer, and a clutch actuated by said spring and carried by the sleeve and acting on said rod for preventing reverse movement of the sleeve.

12. A lubricating means including a lubricant receptacle, a piston therein, a piston rod for said piston, said rod having longi-

tudinal movement relatively to said piston, and clutching or latching mechanism wholly within the receptacle and comprising a plate receiving the rod, means for holding said plate inclined with respect to the axis of the rod on inward movement of the rod, for clutching or latching the said rod against movement relatively to the piston on said inward movement irrespective of the relative positions of said piston and rod and permitting movement of the rod relatively to the piston on the reverse movement of the rod.

Signed at New York, in the county of New York and State of New York, this 8th day of April A. D., 1929.
